UNITED STATES PATENT OFFICE.

ALBERT N. SHELDON, OF VENTURA, CALIFORNIA.

APPARATUS FOR WALKING ON WATER.

Application filed June 14, 1922. Serial No. 563,176.

To all whom it may concern:

Be it known that I, ALBERT N. SHELDON, a citizen of the United States, residing at Ventura, in the county of Ventura and State 5 of California, have invented a new and useful Apparatus for Walking on Water, of which the following is a specification.

This invention relates to an apparatus that will enable a person to walk on water, 10 being an improvement over the disclosure in my former Patent No. 1,384,354, granted July 12, 1921.

An object of the invention is to produce a more substantial construction than disclosed 15 in said patent.

Another object is to minimize friction between the frame and the guides.

Another object is to improve the mechanism whereby the frame is advanced by the 20 advancing float.

Another object is to provide a construction for gradually absorbing the momentum of the advancing float by the frame so as to obtain a glide after the stride is completed.

Another object is to provide a rudder construction that will insure against fouling of the rudder by obstructions in the water.

Another object is to provide a novel steering device.

Another object is to minimize side drift when it is desired to drive the apparatus by the power of the wind.

The accompanying drawings illustrate the invention:

Figure 1 is a plan view of an apparatus constructed in accordance with the provisions of this invention, solid lines indicating the parts in the mid-stride position, and broken lines indicating one of the floats, 35 frame, etc., in the positions they occupy at the end of a stride.

Fig. 2 is a side elevation of Figure 1, partly in section.

Fig. 3 is a sectional elevation on the line indicated by 3-3, Figure 2, the upper portion of the steering column and the steering handle being broken away to contract the view.

Fig. 4 is an enlarged sectional detail on the line indicated by 4-4, Figure 2.

Fig. 5 is a sectional elevation on the line indicated by 5-5, Figure 4.

Fig. 6 is an enlarged fragmental elevation, partly in section, from the line indicated by 55 6-6, Figure 1.

Fig. 7 is an enlarged fragmental elevation, partly in section, of the right portion of Figure 1, the rudder being shown in lowered position in full lines and in elevated position in broken lines.

60

Fig. 8 is a fragmental elevation, partly in section, from the line indicated by 8-8, Figure 1.

There is provided a suitable frame indicated in general by the character 10 and constructed, in this instance, of longitudinally extending outer members 11, longitudinally extending lower inner members 12 and longitudinally extending upper inner members 13. The members 11 converge at 65 their ends and are there connected with the members 12. The members 13 have downwardly bent portions 14 at their front ends connected to each other by a cross member 15. The rear ends of the members 11 are 70 connected by a cross member 16 and the rear ends of the members 13 are connected by a cross member 17. At intervals the members 11, 12 and 13 are connected by transversely 75 extending trusses 18. Preferably the frame 80 10 is principally constructed of seamless steel tubing with the different members welded to one another.

Positioned beneath the frame is a pair of spaced floats 19 extending parallel with one 85 another and decked over, the decks being indicated at 20. The decks 20 are provided with openings 21 through which the operator passes his feet which he places on slats 22 extending longitudinally in the bottom 90 of the floats. In the instance shown in the drawings the floats 19 are divided into a number of water tight compartments 23, 24 so as to insure buoyancy and any water that may accidentally enter the openings 21 will 95 not be able to penetrate into any of said water tight compartments and swamp the apparatus.

The members 11, 12 serve as guides and are engaged by bearings 25 each of which 100 is constructed as follows: A suitable standard 26 is fastened by screws 27 to the deck of the float and it supports four pins 28. On the pins 28 are journaled grooved rollers 29, the pins 28 being positioned to bring 105 the peripheries of the rollers in radial relation to the guides which they engage. The radius of curvature of the peripheries of the rollers, transversely thereof, is slightly greater than the radius of curvature of the 110

guides so as to prevent any tendency to binding between the rollers and the guides. In this particular instance six bearings 25 are provided, one on each of the floats near the outer edge thereof engaging the adjacent member 11, and two on each of the floats near the inner edge thereof engaging the adjacent member 12.

- In order that the frame may be positively advanced half the distance that either of the floats is advanced relative to the other float, the following construction is provided. Pivoted at 30 at its center to a transverse member 31, supported by the members 12, is a lever 32 and pivoted to the outer ends of said lever at 33 are links 34. The rear ends of the links 34 are pivoted at 35 to the decks, respectively, of the floats, preferably along the longitudinal axes of said floats, though such position is not essential. It will now be seen that advancing of either of the floats will swing the lever 32 about one of the pivots 33 acting as a fulcrum, said fulcrum shifting, however, so as to permit the pivot 30 to advance in a straight path. Since the pivot 30 is midway of the distance between the pivots 33, the frame will be advanced just half of the distance traversed by the float.
- Fixed to the cross members 16, 17 is a vertical bearing 36 for a rudder post 37. The lower end of the rudder post 37 is provided with an angular arm 38 carrying a horizontal pivot 39 which passes through forwardly extending arms 40 of a rudder 41. Thus the rudder 41 is hinged to swing in a vertical path, and the forward end of the rudder is rounded downwardly and rearwardly as indicated at 42. If any debris strike the rounded end 42 of the rudder, when the apparatus is moving forward, the rudder will be swung upwardly until it passes over said debris. A triangular steering arm 43 is connected at its ends to the rudder and passes beneath the horizontal leg of the arm 38 to form a stop 44 adapted to contact with the arm 38 to limit downward swinging of the rudder. To the opposite sides of the arm 43 are secured cables 45 which are crossed and extend forwardly and are secured to the opposite ends of arms 46 projecting from opposite sides of a steering shaft 47 having a steering handle 48 at its upper end. The shaft 47 is journaled in a steering column 49 connected by cross members 50 to the frame members 12, 13. Turning of the handle 48 in either direction effects steering of the apparatus in that direction.
- Pivoted horizontally at 51 to the bottom of each float are paddles or fins 52. Each fin is provided with forwardly extending flanges 53 adapted to engage the bottom of the float when the fin is almost vertical with respect to said bottom, so as to hold the fin

against collapsing forwardly and permit the fin to collapse rearwardly. The operation of these fins is well understood in this art.

Pivotedly connected at 54 to the frame members 12 is a center-board 55 rounded downwardly and rearwardly at its forward end as indicated at 56. Secured at the rear upper corner of the center-board 55 is a cable 57 which is fastened at its upper end to the frame. The cable 57 is of a length to permit the center-board to lower into the position shown in Figure 6. The cable 57 is provided with a hook 58 which may be engaged with the frame when the center-board is drawn up, so as to support said center-board in the raised position when it is not desired to use it.

There is provided a yielding stop between the frame and each of the floats constructed as follows: Each float is provided along its median line with a rod 59 and surrounding the rear portions of the rods are coil springs 60. Projecting downwardly from the foremost truss 18 are stops 61, through which the rods 59 can slide and against which the springs 60 strike when the floats are shoved forwardly with respect to the frame.

The invention operates as follows: The pedestrian standing with one foot in one of floats and the other foot resting in the other now be seen that advancing of either of the floats will swing the lever 32 about one of the pivots 33 acting as a fulcrum, said fulcrum shifting, however, so as to permit the pivot 30 to advance in a straight path. Since the pivot 30 is midway of the distance between the pivots 33, the frame will be advanced just half of the distance traversed by the float.

Fixed to the cross members 16, 17 is a vertical bearing 36 for a rudder post 37. The lower end of the rudder post 37 is provided with an angular arm 38 carrying a horizontal pivot 39 which passes through forwardly extending arms 40 of a rudder 41. Thus the rudder 41 is hinged to swing in a vertical path, and the forward end of the rudder is rounded downwardly and rearwardly as indicated at 42. If any debris strike the rounded end 42 of the rudder, when the apparatus is moving forward, the rudder will be swung upwardly until it passes over said debris. A triangular steering arm 43 is connected at its ends to the rudder and passes beneath the horizontal leg of the arm 38 to form a stop 44 adapted to contact with the arm 38 to limit downward swinging of the rudder. To the opposite sides of the arm 43 are secured cables 45 which are crossed and extend forwardly and are secured to the opposite ends of arms 46 projecting from opposite sides of a steering shaft 47 having a steering handle 48 at its upper end. The shaft 47 is journaled in a steering column 49 connected by cross members 50 to the frame members 12, 13. Turning of the handle 48 in either direction effects steering of the apparatus in that direction.

Pivoted horizontally at 51 to the bottom of each float are paddles or fins 52. Each fin is provided with forwardly extending flanges 53 adapted to engage the bottom of the float when the fin is almost vertical with respect to said bottom, so as to hold the fin

against collapsing forwardly and permit the fin to collapse rearwardly. The operation of these fins is well understood in this art.

Pivotedly connected at 54 to the frame members 12 is a center-board 55 rounded downwardly and rearwardly at its forward end as indicated at 56. Secured at the rear upper corner of the center-board 55 is a cable 57 which is fastened at its upper end to the frame. The cable 57 is of a length to permit the center-board to lower into the position shown in Figure 6. The cable 57 is provided with a hook 58 which may be engaged with the frame when the center-board is drawn up, so as to support said center-board in the raised position when it is not desired to use it.

There is provided a yielding stop between the frame and each of the floats constructed as follows: Each float is provided along its median line with a rod 59 and surrounding the rear portions of the rods are coil springs 60. Projecting downwardly from the foremost truss 18 are stops 61, through which the rods 59 can slide and against which the springs 60 strike when the floats are shoved forwardly with respect to the frame.

The invention operates as follows: The pedestrian standing with one foot in one of floats and the other foot resting in the other

now be seen that advancing of either of the floats will swing the lever 32 about one of the pivots 33 acting as a fulcrum, said fulcrum shifting, however, so as to permit the pivot 30 to advance in a straight path. Since the pivot 30 is midway of the distance between the pivots 33, the frame will be advanced just half of the distance traversed by the float.

Fixed to the cross members 16, 17 is a vertical bearing 36 for a rudder post 37. The lower end of the rudder post 37 is provided with an angular arm 38 carrying a horizontal pivot 39 which passes through forwardly extending arms 40 of a rudder 41. Thus the rudder 41 is hinged to swing in a vertical path, and the forward end of the rudder is rounded downwardly and rearwardly as indicated at 42. If any debris strike the rounded end 42 of the rudder, when the apparatus is moving forward, the rudder will be swung upwardly until it passes over said debris. A triangular steering arm 43 is connected at its ends to the rudder and passes beneath the horizontal leg of the arm 38 to form a stop 44 adapted to contact with the arm 38 to limit downward swinging of the rudder. To the opposite sides of the arm 43 are secured cables 45 which are crossed and extend forwardly and are secured to the opposite ends of arms 46 projecting from opposite sides of a steering shaft 47 having a steering handle 48 at its upper end. The shaft 47 is journaled in a steering column 49 connected by cross members 50 to the frame members 12, 13. Turning of the handle 48 in either direction effects steering of the apparatus in that direction.

Pivoted horizontally at 51 to the bottom of each float are paddles or fins 52. Each fin is provided with forwardly extending flanges 53 adapted to engage the bottom of the float when the fin is almost vertical with respect to said bottom, so as to hold the fin

absolutely necessary to the operation of the apparatus.

It will be clear that, as the floats are shoved forwardly relative to the frame, the frame and the bearings 25 will prevent separation of the frame and floats with the production of very little friction. The frame and float, by the bearings described, will be held against relative movement in a

10 vertical direction and also laterally.

An important advantage of the springs 60 and stop 61 is that the motion of the forwardly moving float is gradually absorbed by the other float so as to start said other

15 float forwardly without muscular effort of the operator.

The construction of the frame and bearings described makes it possible to carry considerable luggage and a plurality of operators without the production of undue friction between the frame and bearings.

I claim:

1. In an apparatus for walking on water, a frame, parallel floats beneath the frame, 25 means shiftably supporting the frame on the floats, a lever pivoted near its middle to the frame, and links pivoted to the ends of the lever and to the floats respectively.

2. In an apparatus for walking on water, 30 a frame, spaced parallel floats beneath the frame, means shiftably supporting the frame on the floats, means operable by forward motion of either of the floats to advance the frame with respect to the other float, a center board pivotally suspended at its forward end from the frame in the space between the floats, and means to limit downward swinging of the center board.

3. In an apparatus for walking on water, 40 a frame, parallel floats beneath the frame, means shiftably supporting the frame on the floats, means operable by forward motion of either of the floats to advance the frame with respect to the other float, a rudder post journaled on the frame, an arm fixed to the lower end of the rudder post and carrying a horizontal pivot, a rudder connected with the

pivot, means to limit downward swinging of the rudder, and operating means for the rudder.

50

4. In an apparatus for walking on water, a frame, parallel floats beneath the frame, means shiftably supporting the frame on the floats, means operable by forward motion of either of the floats to advance the frame with respect to the other float, a rudder post journaled on the frame, a rudder connected with the rudder post, a column mounted on the frame, a shaft journaled in the column, a steering handle on the upper end of the shaft, a bar on the lower end of the shaft, and means operably connecting the bar with the rudder.

55

5. In an apparatus for walking on water, a frame having longitudinal members forming guides, parallel floats beneath the frame, means operable by forward motion of either of the floats to advance the frame with respect to the other float, the guides being tubular, standards mounted on the floats, and 60 rollers rotatably mounted on the standards with their peripheries radially of the guides.

65

6. In an apparatus for walking on water, a frame having longitudinal outer members and longitudinal upper and lower inner members and having trusses connecting said members at intervals, parallel floats beneath the frame, means shiftably supporting the frame on the floats, and means operable by forward motion of either of the floats to advance the frame with respect to the other float.

75

7. In an apparatus for walking on water, a frame, parallel floats beneath the frame, means shiftably supporting the frame on the floats, means operable by forward motion of either of the floats to advance the frame with respect to the other float, and means yieldingly limiting the forward motion of the floats in relation to the frame.
